(57) **CLAIM**

The ornamental design for a transient voltage surge protector, as shown and described.

DESCRIPTION

FIG. 1 is a perspective view of an transient voltage surge protector showing our new design;

FIG. 2 is a right side view of the transient voltage surge protector shown in FIG. 1;

FIG. 3 is a top view of the transient voltage surge protector shown in FIG. 1;

FIG. 4 is a front view of the transient voltage surge protector shown in FIG. 1;

FIG. 5 is a bottom view of the transient voltage surge protector shown in FIG. 1;

FIG. 6 is a left side view of the transient voltage surge protector shown in FIG. 1; and,

FIG. 7 is a rear view of the transient voltage surge protector shown in FIG. 1.
